US0D1037049S

(12) **United States Design Patent** (10) **Patent No.:** **US D1,037,049 S**
(45) **Date of Patent:** **** Jul. 30, 2024**

(54) **WATCH DIAL**

(71) Applicant: **Parmigiani Fleurier S.A.**, Fleurier (CH)

(72) Inventor: **Michel Parmigiani**, Fleurier (CH)

(73) Assignee: **PARMIGIANI FLEURIER S.A. (CH)**

(**) Term: **15 Years**

(21) Appl. No.: **29/828,235**

(22) Filed: **Feb. 25, 2022**

(30) **Foreign Application Priority Data**

Aug. 26, 2021 (WO) WIPO107812

(51) **LOC (14) Cl.** **10-07**

(52) **U.S. Cl.**

USPC **D10/126**

(58) **Field of Classification Search**
